UNITED STATES PATENT OFFICE.

JOSEPH PHELPS, OF BELLEVILLE, NEW JERSEY, ASSIGNOR TO REMINGTON TYPE-WRITER COMPANY, OF ILLION, NEW YORK, A CORPORATION OF NEW YORK.

TYPEWRITING-MACHINE.

1,356,827.

Specification of Letters Patent.

Patented Oct. 26, 1920.

Application filed January 18, 1919. Serial No. 271,797.

To all whom it may concern:

Be it known that I, JOSEPH PHELPS, a citizen of the United States, and resident of Belleville, in the county of Essex and State 5 of New Jersey, have invented certain new and useful Improvements in Typewriting-Machines, of which the following is a specification.

My invention relates to typewriting machines and it has for its object to effect certain improvements in the control of the carriage, especially with respect to securing a uniform left-hand margin to the writing.

To the above and other ends, my invention 15 consists in certain features of construction and combinations and arrangements of parts all of which will be set forth herein and particularly pointed out in the claims.

In the accompanying drawings,

20 Figure 1 is a fragmentary front view showing the carriage escapement mechanism and my improvements and some associated parts of the machine, portions of which are in vertical section.

25 Fig. 2 is a plan view in section on the line 2—2 of Fig. 1.

Fig. 3 is a sectional view on the line 3—3 of Fig. 2 and looking toward the rear of the machine.

30 Fig. 4 is a rear elevation of the escapement mechanism wheel and the bracket on which it is mounted and showing the rear end portion of my improvements.

Fig. 5 is a perspective view on a small 35 scale of the bracket in which the escapement wheel and the movable parts of my improvements are mounted.

Figs. 6 to 9 inclusive show a modified form of the invention.

40 Fig. 6 is a view of said modified form somewhat similar to Fig. 1 but with parts of the mechanism shown in section on line 6—6 of Fig. 7.

Fig. 7 is an enlarged top plan view with 45 parts in section on the line 7—7 of Fig. 6.

Fig. 8 is an enlarged view, partly in section, on the line 8—8 of Fig. 7 and also with parts broken away.

Fig. 9 is an enlarged fragmentary view 50 in section on the line 9—9 of Fig. 7.

I have shown my invention embodied in one form of Remington typewriting machine, the main frame of which includes a top plate 11, the middle rear part of which 55 only is shown. Said top plate has a good

sized notch or cut-out indicated in the drawings by the lines 12, said cut-out being partly for the accommodation of the escapement mechanism and partly for the accommodation of certain tabulator mechanism not 60 shown. In Fig. 3 are shown two ears 13, the purpose of which is to secure in place certain tabulator frame-work with which the present invention is not concerned.

The machine to which my invention is 65 here applied includes a set of front-strike type bars which operate a universal bar, which universal bar is connected with a link 14, Figs. 1 and 6, that operates the escapement, said link 14 being moved toward 70 the rear of the machine on the positive stroke of any type bar and returning toward the front of the machine on the return stroke of the type bar. Of the carriage of the machine nothing is shown except the feed rack 75 15 which meshes with a feed pinion 16 which is connected with the escapement mechanism. Said carriage is normally drawn toward the operator's left by means of a spring drum 17 acting through a tape 18. 80

A shaft 20 is journaled at its ends in a bracket 21, which bracket is secured by screws to the top plate 11 at 22. At its rear end the shaft 20 has mounted thereon the exteriorly threaded hub 23 of a ratchet wheel 24 and onto said threaded hub there is screwed the hub 25 of a disk or gear wheel 26, the two hubs 23 and 25 being fastened to the shaft 20 by means of a set screw 27 passing through both of said hubs. 85

The escapement wheel proper 28 is secured to the rear face of the disk or wheel 26 by means of screws 30. The pinion 16 is fast

on or integral with the forward end of a hollow shaft 31 which at its forward end is journaled on the shaft 20 and at its rear end on a reduced portion of the hub 23. At its rear end said sleeve or shaft 31 is widened out to form a barrel 32 having a pawl 33, Fig. 3, pivoted therein and pressed by a 90

spring 34 into engagement with the ratchet wheel 24, the construction being such that when the carriage is traveling in forward or letter feed direction the shaft 20 and escapement wheel 28 are positively driven with the pinion 16, but when the carriage is moving in reverse direction, that is, toward the operator's right, said pinion can turn independently of said shaft and escapement wheel. 95

A dog rocker 35 is pivoted on cone pivots 36 mounted in a bracket 37 secured to the underside of the top plate 11 and said dog rocker has a depending arm 38 to which the link 14 is connected, the whole construction being such that on a positive stroke of a key or of the space bar the arm 38 moves toward the rear of the machine and the upper part of the dog rocker toward the front of the machine. The extreme upper part of the dog rocker 35 is formed into a fixed beveled dog 40 and a loose or stepping dog 41 is pivoted to the front face of said dog rocker on a pivot 42 with freedom to 15 vibrate between two stops 43 and 44. Any suitable detent may be provided to prevent backward rotation of the escapement wheel 28 when rack 15 is raised out of mesh with pinion 16 to release the carriage. The dog rocker shown and described is or may be of the sort shown and claimed in the application of George A. Seib, Serial No. 118,607, filed September 6, 1916.

In the escapement described the parts normally stand as shown in the drawings. When a character key or the space key is operated the lower end of the dog rocker is moved toward the rear and the upper part of said dog rocker toward the front of the machine, thus moving the stepping dog 41 out of engagement with one of the teeth 45 of the escapement wheel and the rigid dog 40 into engagement with said tooth. The stepping dog when moved out is immediately thrown over by its spring 46 against the stop 43 and when the space bar or universal bar returns to normal position and the upper part of the dog rocker moves toward the rear, said stepping dog moves back into the path of the next oncoming tooth 45 which strikes it and forces it back against the stop 44. As the carriage moves along step-by-step it will ultimately be arrested by a line lock stop, and it is the intention that the keys at this time be locked against operation, but as a matter of fact in very rapid writing the dog rocker does sometimes get an extra operation after the carriage has been arrested. In that event the loose dog 41 will have been moved out of engagement with the lowermost tooth 45 and will have dropped back against its stop 43; but as the carriage has been arrested the escapement wheel will not turn and when the dog rocker returns to normal position the dog 41 will be in the position shown by dotted lines in Fig. 3, and this dog and the wheel 28 will be in a false relative position, which may be described as an escaped disarrangement of the members of the escapement. If now the carriage be withdrawn toward the right until it is arrested by the margin stop and then be restored to the control of the escapement, it 65 will happen if nothing be provided to pre-

vent it, that the wheel will not stay in the position shown in Fig. 1 but the carriage will be drawn by its spring one step toward the left until the tooth 45 at the right of the dog 41, as shown in dotted lines in Fig. 3, comes down to lowermost position. The carriage will therefore take a false step so that if the margin stop had been set for letter space position 10, for example, the carriage will as a matter of fact come to 75 rest at letter space position 11 and that particular line of writing will not begin in conformity to the other lines on the page. The false position of the dog 41 and the resulting false step of the carriage can also 80 be brought about under conditions of operation other than the one described, as for example by the operator striking a letter key or a space key after the carriage has begun its return motion. I have provided 85 means to cure the defective operation mentioned.

In some prior construction it has been sought to remedy the described defect by providing in addition to the feed dogs 40 and 41, a third or so-called "margin dog" which when the dog 41 is in the false position shown in Fig. 3 itself takes hold of the lowermost tooth 45 in place of said dog 41; but my invention involves a different 95 principle in this respect, that instead of providing a substitute for the misplaced dog 41 I provide means for correcting the relative positions of said dog and the escapement wheel. In the present instance this is 100 done by moving said escapement wheel into proper relation to the dog 41. This can be done theoretically by moving the escapement wheel in either direction. Thus if said wheel be moved in counter-clockwise direction in Fig. 3, that is to say, in the same direction that it turns when the carriage is stepping, the next oncoming tooth of the escapement wheel will strike the dog 41 and press it back into its normal position shown 110 in Fig. 1; and this is the mode of operation in the present instance. I have also invented means for moving the wheel in the opposite direction, forcing the lowermost tooth 45 to the left in Fig. 3, past the misplaced 115 dog 41, the same being set forth and specifically claimed in my co-pending application filed Jan. 23, 1919, Sr. No. 272,682. I purpose in this case to make claims broad enough to cover both of these schemes, as 120 well as claims limited to the specific form of the invention herein described.

In the form of the invention shown in Figs. 1 to 5 inclusive, I mount in the bracket 21 a counter-shaft 47 having a pinion 48 fast on its forward end and in position to engage the feed rack 15 a little to the right of the pinion 16, so that said pinion 48 is positively turned in one direction or the other as the carriage moves to the left or 130

right. Near its rear end said shaft 47 has journaled thereon a hub 50 of a drum 51 constructed so that there is an annular space between said hub and the cylindrical part 5 of said drum. A gear wheel 52 has its hub extending into said annular space and journaled on the outside of the hub 50, said gear wheel 52 meshing with the gear wheel 26 that is connected with or practically forms 10 a part of the escapement wheel 28. The construction includes a slip joint which can be variously located. As here shown, in front of the drum 51 a disk 53, preferably of fiber or other suitable frictional material, 15 is mounted on the shaft 47 to which it is connected by means of a pin 54, Fig. 2, said pin passing through the shaft and into a notch in the disk 53 and constituting in effect a splined connection between said disk 20 and the shaft so that the disk is compelled to rotate with the shaft but can move longitudinally thereof so far as the pin 54 is concerned. The disk 53 is pressed into frictional contact with the drum 51 by means of 25 a spider-shaped spring 55 which is compressed between said disk and a collar 56 mounted on the shaft 47 and secured in place by a set screw 57. The thrust of the spring 55 is taken by a washer 58 mounted on the 30 reduced rear end of the shaft 47 and held in place by nuts 60. The construction is such that the spring 55 and disk 53 tend frictionally to cause the drum 51 to turn with the shaft 47 but these parts can be 35 turned independently of one another by a force sufficient to overcome the friction. The drum 51 is connected with the wheel 52 by means of a one-way-acting clutch, that shown being a roller clutch consisting of a 40 roller 61 mounted in a notch 62 in the hub of the wheel 52 and acted on by a very light spring 63. This clutch enables the drum 51 to turn independently of the wheel 52 when the carriage is moving in forward or letter 45 feed direction but constitutes in effect a positive connection between said drum and wheel when the carriage is moving in reverse direction toward the beginning of a new line of writing. As a matter of fact, 50 as will be readily understood, when the carriage is moving forward the drum 51 and wheel 52 turn in opposite directions but the parts run freely at this time. The slip joint 53 tends constantly during the reverse 55 movement of the carriage to turn the escapement wheel 28 in its forward direction so that even if the space key, for example, be operated while the carriage is in motion toward the right, the escapement wheel will 60 take a full step and come to correct position. It will be perceived that the escapement wheel 28 is geared to the carriage in the usual way, but that I have provided in addition 65 secondary gearing to control said wheel during reverse motion of said carriage.

The bracket 21 is here shown of a construction modified to accommodate the new elements just described, as best shown in Fig. 5, where it will be seen that said bracket has two ears 64 in which the shaft 70 47 is journaled, and that the arm 65 of said bracket is elevated so as not to interfere with the gear wheel 52.

In operation, when the carriage is moving in letter feeding direction, as in the 75 operation of writing, both pinions 16 and 48 will be turned in the same direction and the escapement wheel 28 will be turned in its usual or forward direction, namely, in the direction of the arrow in Fig. 3, this 80 turning of the wheel being positive through the medium of the one-way-acting clutch consisting of the pawl 33 and ratchet wheel 24. At this time the gear wheel 26 is positively turned and therefore the gear wheel 85 52 is positively turned in the opposite direction, at which time the roller clutch 61 is loose and offers practically no resistance to the turning. When the carriage is drawn back toward the right to begin a new line, 90 both pinions 16 and 48 are turned in the reverse direction, but at this time the pawl and ratchet 33, 24 are inactive and the roller clutch 61 is active so that the drum 51 cannot turn independently of the wheel 95 52, and said drum and wheel are therefore subjected to the full friction of the disk 53 which is pressed by the spider 55 against the drum 51 at a distance from the axis of 100 rotation, so that this friction is of an appreciable amount. The tendency of said friction is to turn the wheel 52 in the same direction that it was turned positively by the gear 26 when the carriage was moving 105 toward the left, and said gear 52 therefore tends to turn the escapement wheel in forward or letter feed direction. The friction at 53 is ample to overcome the force of the spring 46 that controls the stepping dog and the escapement wheel will therefore be held in its normal position by friction with the stepping dog pressed back against the stop 44, as shown in Figs. 1 and 3. In case the stepping dog 41 has 110 made a false step, as above described into the position shown in dotted lines in Fig. 3, this false position will be instantly corrected when the carriage begins to move toward the right by the frictional connection described; that is to say, by the turning of the escapement wheel 28 in letter feed direction through the instrumentality of the gear wheel 52 and the frictional connection 53. As soon as the wheel is moved to the position shown in Fig. 1, it is positively arrested and from that time on during a rightward movement of the carriage the friction disk 53 rubs against the drum 51, which is, however, held stationary. The 115 result is that at the instant when the car- 120

125 130

riage comes against the margin stop the escapement wheel is standing in its Fig. 1 position in proper relation to the stepping dog 41, whether or not said stepping dog had at the beginning of said rightward motion been standing in its correct position or in its incorrect position. It will thus be seen that the margin will be uniform because at the time when the carriage is restored to the influence of its escapement, after being arrested by the margin stop, said escapement will be standing in the same position, irrespective of whether or not the stepping dog had gotten into a false position. By my improvements, therefore, the incorrect relative position of the escapement wheel and stepping dog is corrected automatically by the return motion of the carriage.

Another form of my invention is shown in Figs. 6 to 9 inclusive. In this form of the invention the construction of the typewriter and its escapement is identical with the form shown in Figs. 1 to 5, and the corresponding parts are designated in these figures by the same reference numerals; but the bracket 21^a in this form of the invention is of the usual shape and not modified as in Fig. 5. In this instance, the pinion 16 alone engages the rack 15 and another pinion 66 is rigid on the hollow shaft or sleeve 31. Said pinion 66 meshes with an idler gear 67 journaled on a screw 68 threaded into a bracket 70, which bracket 25 is secured by means of a screw 71 to the top surface of the bracket 21^a. The bracket 70 as here shown consists of a piece of sheet metal bent up into U-shape to form two vertical arms in which is journaled a counter-shaft 72 having fixed on its rear end a pinion 73 that meshes with the idler 67, the construction being such that the shaft 72 turns always in the same direction as the hollow shaft 31. On the rear end of the shaft 72 there is mounted a disk or washer 74 and abutting against said disk is the elongated hub 75 of a drum 76 corresponding in this form of the invention to the drum 51 of the other form. A pinion 50 77 meshing with the gear 26 has its hub 78 journaled on the hub 75 and said hub 78 is operatively connected with the drum 76 by means of a roller clutch 80, similar in function to the roller clutch 61 of the preceding 55 form of the invention. A friction disk 81 is mounted on the shaft 72 with which it is connected by a spline pin 82 and said disk is pressed against the drum 76 by means of a spring-spider 83 compressed between said 60 disk and a collar 84 on the shaft 72. It will be perceived that whereas this form of the invention differs in details from the first form, the only essential difference is in the form of gearing between the counter-shaft 65 and the feed rack, both forms of gearing,

however, having the effect of making the hollow shaft of the escapement and said counter-shaft turn in the same direction whenever either of them is turned by the rack 15.

In both forms of the invention I have so proportioned the gearing that a given extent of motion of the rack 15 toward the operator's right turns the escapement wheel to a less extent than the same motion of said rack toward the operator's left. In other words, the gear wheel 26 is larger than either of the gears 52 and 77, and in Fig. 1 the pinion 48 is a little larger than the pinion 16.

Various changes other than those particularly referred to hereinabove, may be made in the details of construction and arrangement without departing from my invention.

What I claim as new and desire to secure by Letters Patent, is:—

1. In a typewriting machine, the combination of a carriage, an escapement mechanism the members of which are liable to an escaped disarrangement, and an automatic correcting device.

2. In a typewriting machine, the combination of a carriage, an escapement mechanism one of the members of which is capable of an escape step, and a correcting device operative on said member.

3. In a typewriting machine, the combination of a carriage, an escapement mechanism, and a correcting device automatically operative on said escapement mechanism by a reverse movement of the carriage.

4. In a typewriting machine, the combination of a carriage, an escapement mechanism, a correcting device operative thereon, and means between the carriage and the correcting device for actuating the latter upon a movement of the carriage.

5. In a typewriting machine, the combination of a carriage, an escapement mechanism including a toothed wheel and a loose dog, and a correcting device for moving one of said escapement members into proper relationship to another when said members shall have become disarranged by the movement of the loose dog to the wrong side of a wheel tooth.

6. In a typewriting machine and in carriage controlling mechanism, the combination with a power driven carriage, an escapement wheel, and a loose dog, said wheel and dog being liable to get into a false relation, of means for automatically correcting said false relation between said wheel and dog.

7. In a typewriting machine and in carriage controlling mechanism, the combination with a power driven carriage, an escapement wheel, and a loose dog, said wheel and dog being liable to get into a false relation, of means operated by said carriage in its reverse movement to begin a new line for

- automatically correcting said false relation between said wheel and dog.
8. In a typewriting machine and in carriage controlling mechanism, the combination with a power driven carriage, an escapement wheel, and a loose dog, said wheel and dog being liable to get into a false relation, of means operated by the carriage in its reverse movement to begin a new line for im-
10 parting a turning movement to said wheel such as to bring a tooth of said wheel into correct relation with said loose dog.
9. In a typewriting machine and in carriage controlling mechanism, the combination with a power driven carriage, an escapement wheel connected with said carriage by pawl and ratchet mechanism, and feed dogs, of means operated by the return movement of said carriage for positioning said escape-
15 ment wheel independently of said pawl and ratchet mechanism.
10. In a typewriting machine and in carriage controlling mechanism, the combination of a power driven carriage, an escapement wheel, and feed dogs therefor, of means whereby said escapement wheel is positively driven by the carriage during the letter space feed of the carriage, and separate means inactive during said letter space feed but operated by the return movement of the carriage for setting said wheel into proper relation to the said feed dogs.
11. In a typewriting machine and in carriage controlling mechanism, the combination with a power driven carriage, and an escapement wheel, of means operated by the return motion of the carriage for setting said wheel at a definite position.
12. In a typewriting machine, the combination of an escapement including a toothed wheel and a loose dog, of means for automatically moving said wheel and dog one relatively to the other, to correct said members when they get into a false position.
13. In a typewriting machine, the combination of an escapement including a toothed wheel and a loose dog, of means controlled by a reverse carriage movement for automatically moving said wheel and dog one relatively to the other, to correct said members when they get into a false relation.
14. In a typewriting machine, the combination of an escapement including a toothed wheel and a loose dog, a normally inactive correcting device, and means connected with the carriage for causing said device to move said wheel and dog one relatively to the other, to restore the escapement mechanism to normal relationship.
15. In a typewriting machine, the combination with a carriage, of an escapement wheel, gearing connecting said wheel with said carriage, secondary gearing between said wheel and carriage, and means where-
60 by said secondary gearing acts on said

wheel when the carriage is being returned toward position for beginning a new line of writing.

16. In a typewriting machine, the combination with a carriage, of an escapement wheel, gearing connecting said wheel with said carriage, secondary gearing between said wheel and carriage, and means including a one-way-acting clutch whereby said secondary gearing acts on said wheel when the carriage is being returned toward position for beginning a new line of writing.

17. The combination with a carriage of an escapement wheel, means whereby said wheel is positively turned as the carriage steps in letter feed direction, and means tending to turn said wheel in the same direction as before, when the carriage is moving in the opposite direction.

18. The combination with a carriage, of escapement mechanism including an escapement wheel and dog, means for turning said wheel in one direction when the carriage is moving toward the left, and means for turning said wheel in the same direction a limited distance when the carriage is moving toward the right to correct any false step of said dog.

19. The combination with a carriage of an escapement wheel and means for turning said wheel in the same direction when the carriage is moving toward the left and toward the right, said means acting positively in one direction of carriage movement and frictionally in the other.

20. In a typewriting machine, the combination with a carriage and an escapement including an escapement wheel, of means tending constantly during the reverse movement of said carriage to turn said wheel forward.

21. In a typewriting machine, the combination with a carriage and an escapement including an escapement wheel, of means including a counter-shaft and gearing for turning said wheel forward by a reverse movement of the carriage.

22. In a typewriting machine, the combination with a carriage and an escapement including an escapement wheel, of means including a counter-shaft and gearing and a slip joint tending constantly during the reverse movement of the carriage to turn said wheel forward.

23. In a typewriting machine, the combination with a carriage and an escapement including an escapement wheel, of means including a slip joint tending constantly during the reverse movement of said carriage to turn said wheel.

24. In a typewriting machine, the combination with a carriage and an escapement including an escapement wheel, of a train of connections from said carriage to said wheel including a slip joint and a one-way

125

130

clutch, said clutch operating during the reverse movement of said carriage.

25. In a typewriting machine, the combination with a carriage and an escapement including an escapement wheel, of connections between said carriage and said wheel including two one-way clutches, one acting on the forward and the other on the reverse movement of the carriage, and a slip joint operatively associated with the latter clutch.

26. In a typewriting machine, the combination with carriage escapement mechanism including an escapement wheel, of a counter-shaft geared to the carriage, a gear loose on said countershaft and geared to said escapement wheel, a drum loose on said countershaft, a one-way-acting connection between said gear and said drum, and a slip-joint between said drum and said counter-shaft.

27. In a typewriting machine, the combination of a carriage feed rack, a feed pinion meshing with said rack, an escapement wheel operated by said pinion during forward motion of said carriage, feed dogs

controlling said wheel, a second pinion 25 meshing with said rack, and means operated by said second pinion for controlling said wheel during reverse movement of the carriage.

28. In a typewriting machine, the combination of a carriage feed rack, a feed pinion meshing with said rack, an escapement wheel operated by said pinion during forward motion of said carriage, feed dogs 30 controlling said wheel, a counter-shaft having a pinion meshing with said rack, and means including a slip-joint and a one-way-acting connection whereby said counter-shaft controls said escapement wheel during reverse movement of said carriage. 35

Signed at the borough of Manhattan, city of New York, in the county of New York and State of New York this 13th day of January, A. D. 1919.

JOSEPH PHELPS.
